US00D938494S

(12) **United States Design Patent** (10) **Patent No.:** **US D938,494 S**
Zhou et al. (45) **Date of Patent:** **** Dec. 14, 2021**

(54) **DISPLAY SCREEN OR PORTION THEREOF WITH A GRAPHICAL USER INTERFACE**

(71) Applicant: **BEIJING KONGMING TECHNOLOGY CO., LTD.**, Beijing (CN)

(72) Inventors: **Jinyao Zhou**, Beijing (CN); **Yunling Feng**, Beijing (CN); **Libin Chen**, Beijing (CN); **Lu Yu**, Beijing (CN)

(73) Assignee: **BEIJING KONGMING TECHNOLOGY CO., LTD.**, Beijing (CN)

(**) Term: **15 Years**

(21) Appl. No.: **29/766,517**

(22) Filed: **Jan. 15, 2021**

(30) **Foreign Application Priority Data**

Jul. 21, 2020 (CN) 202030400057.7

(57) **CLAIM**

The ornamental design for a display screen or portion thereof with a graphical user interface, as shown and described.

DESCRIPTION

The FIGURE is a front view of a display screen or portion thereof with a graphical user interface showing our new design.

The outermost broken line rectangle illustrates a display screen or portion thereof and forms no part of the claimed design.

1 Claim, 1 Drawing Sheet
